INVENTOR:
ROGER W. McBRIEN
BY Harry A. Barnes
ATTORNEY.

UNITED STATES PATENT OFFICE.

ROGER W. McBRIEN, OF ALTON, ILLINOIS.

THERMOSTATICALLY-OPERATED ELECTRIC SWITCH.

Application filed July 15, 1925. Serial No. 43,785.

My invention has relation to improvements in thermostatically operated electric switches and consists in the novel features of construction fully set forth in the specification 5 and pointed out in the claim.

Briefly, the invention consists in providing a receptacle, part of which is made of insulating material and part being made of an electric conducting material, within 10 which is a conductor, the end of said conductor being in slightly spaced relation with the conducting part of the receptacle. Placed within the receptacle and normally 15 out of contact with the conductor and metallic part of the receptacle is a fluent conductor such as mercury which is caused by application of heat to change its position so as to short circuit the conductor and the metallic part of the receptacle thereby closing 20 a suitable signal circuit.

The principal object of the invention is to provide a switch that may be operated by slight increases in temperature above normal atmospheric temperature so as to close 25 a suitable alarm circuit or any other circuit containing an electrical device that it is desired to bring into operation at such increase in temperature. A further object is to provide a switch of this character that is simple 30 in its construction, that may be cheaply manufactured and one that may be repeatedly used unless it is subjected to abnormally high temperatures and destroyed, such as would be the case in event of fire, after the 35 switch had been used to close an electric alarm circuit. Further advantages will be better apparent from a detailed description of the invention in connection with the accompanying drawings, in which—

40 Figure 1 is a middle vertical longitudinal section through my improved thermostatic switch; and Fig. 2 is an end view thereof.

Referring to the drawings, 1 represents a cylinder, preferably porcelain, provided with 45 an annular groove 2 near each end thereof and 3, 3 are metallic cones disposed over the ends of the cylinder 1 and crimped into the grooves 2, 2. Thus, the receptacle consists of an intermediate insulated portion, the 50 cylinder 1, and terminal conducting portions, the cones 3, 3. At the apex of each cone 3 is a boss 4 projecting from which is a threaded stem 5 to which may be secured a conductor 6 by means of the nut 7. On 55 opposite sides of the cylinder 1 and medially disposed are openings 8 through

which are led conductors 9, 9, one being turned toward one end of the receptacle and terminating in close proximity to one of the cones 3, and the other conductor being turned 60 toward the opposite end of the cylinder and terminating close to the opposite cone 3. After the conductors have been disposed within the receptacle, the openings are properly sealed with an insulating material for 65 a purpose that will presently appear. Within the receptacle there is inserted a wall 10 of wax or equivalent material which has insulating properties and at the same time fuses at a comparatively low temperature. 70 By comparative low temperature is meant a temperature but slightly above normal atmospheric temperatures; for example, 110° F. Disposed within the receptacle and between the wall of insulating material 10 and 75 one of the cones 3 is a quantity of mercury 11 or some other normally fluent conductor, such as carbon in pulverulent condition. At each end of the receptacle and secured to each cone 3 is a hanger 12 by which the 80 switch may be supported in the desired location on a hook or equivalent support. A conductor 13 is connected at one end to conductor 9 and at the opposite end to an alarm 14 or other electrical device, said alarm also 85 being connected by conductor 15 to line wire 16. Connected on the binding post 5 is a conductor 17, said conductor 17 being connected also to the line wire 18, thus the alarm 14 is in series with the conductor 9 and cone 90 3, and will be actuated on closing the circuit between said conductor and cone.

In operation, the switch is disposed with its longitudinal axis perpendicular, the cones being one above the other and the mercury 95 being held in the upper part of the receptacle by means of the wall of insulating material 10. If the switch is now subjected to an increase in temperature sufficient to melt the material 10, obviously the mercury will 100 gravitate to the bottom of the receptacle and the melted wax will float on the top of the body of mercury. As the mercury gathers in the bottom of the receptacle it will of course make contact with the bottom cone 3 105 and lower conductor 9 thus closing the electric circuit of which these two members form a part and sounding the alarm 14 or operating the electrical device that is in this circuit. After the switch has been operated, 110 the mercury has settled to the bottom of the receptacle and the wax on top thereof so

that in order to again operate the switch it will be necessary to invert the same so that the mercury will again be at the top thereof and in contact with the conductor 9 and cone 3 to which the circuit wires have not been connected.

Having described my invention, I claim:

A thermostatic switch consisting of a receptacle comprising a cylindrical insulating member, a hollow metallic cone secured to each end of said insulating member, a bind-

ing post on the apex of each cone, a pair of conductors traversing said insulating member and each terminating adjacent to one of the cones, a fusible insulating wall within the insulating member intermediate the cones and enveloping said conductors, and a normally fluent conductor disposed between said wall and one of the cones.

In testimony whereof I hereunto affix my signature.

ROGER W. McBRIEN.
